Primary Examiner — Cynthia M Chin(74) *Attorney, Agent, or Firm* — Knobbe, Martens, Olson & Bear LLP(57) **CLAIM**

The ornamental design for an electric scooter, as shown and described.

DESCRIPTION

FIG. 1 is a perspective view showing top, left and rear sides of an electric scooter.

FIG. 2 is a right side view of the electric scooter of FIG. 1.

FIG. 3 is a left side view of the electric scooter of FIG. 1.

FIG. 4 is a front view of the electric scooter of FIG. 1.

FIG. 5 is a rear view of the electric scooter of FIG. 1.

FIG. 6 is a top view of the electric scooter of FIG. 1; and,

FIG. 7 is a bottom view of the electric scooter of FIG. 1.

Where utilized, the broken lines show portions of the electric scooter that form no part of the claimed design.
